DISPLAY PLATE FOR AN AUTOMOBILE

Sidney M. Polhemus, Jr., Forest Hills, N. Y.

Application March 31, 1950, Serial No. 8,900

Term of patent 14 years

(CL. D14—6)

To all whom it may concern:

Be it known that I, Sidney Merritt Polhemus, Jr., a citizen of the United States, residing at Forest Hills, city and State of New York, have invented a new, original, and ornamental Design for a Display Plate for an Automobile, of which the following is a specification, reference being had to the accompanying drawing, forming a part hereof.

The single figure of the drawing is a front elevational view of a display plate for an automobile, showing my new design.

I claim:

The ornamental design for a display plate for an automobile, as shown.

SIDNEY M. POLHEMUS, JR.
